Design No. 16,661, dated April 27, 1886.

UNITED STATES PATENT OFFICE.

WALLACE N. KENYON, OF BIRMINGHAM, CONNECTICUT, ASSIGNOR TO THE SILVER PLATE CUTLERY COMPANY, OF SAME PLACE.

DESIGN FOR THE ORNAMENTATION OF KNIFE-HANDLES.

SPECIFICATION forming part of Design No. 16,661, dated April 27, 1886.

Application filed March 29, 1886. Serial No. 197,047. Term of patent 3½ years.

To all whom it may concern:

Be it known that I, WALLACE N. KENYON, a citizen of the United States, residing at Birmingham, in the county of New Haven and State of Connecticut, have invented and produced a new and original Design for Ornamentation of Knife and Fork Handles; and I do declare the following to be a full, clear, and exact description of the same, reference being had to the accompanying photographic illustration, forming a part thereof, showing a knife-handle ornamented according to my new design.

The leading feature of my design consists of raised diamond-shaped figures on the knife-handle, alternating with depressed diamond-shaped figures, the two sets of figures com-

pletely covering the surface of the handle. The raised diamond-shaped figures *a* are represented as having smooth surfaces, while the depressed figures *b* are represented as having roughened surfaces.

I claim—

The design for the ornamentation of knife and other similar handles herein shown and described, the same consisting of raised smooth-surfaced diamond-shaped figures alternating with depressed rough-surfaced portions.

In testimony whereof I affix my signature in presence of two witnesses.

WALLACE N. KENYON.
